[57] **CLAIM**

The ornamental design for a ceiling or wall-mounted TV monitor support, as shown and described.

DESCRIPTION

FIG. 1 is a bottom, front, and left side perspective view of a ceiling or wall-mounted TV monitor support showing our new design;

FIG. 2 is a reduced rear elevational view thereof;
FIG. 3 is a reduced right side elevational view thereof,
the left side being a mirror image of that shown;
FIG. 4 is a reduced bottom plan view thereof; and,
FIG. 5 is a reduced front elevational view thereof.

FIG.2

FIG.4

FIG.1

FIG.3

FIG.5
